UNITED STATES PATENT OFFICE

MICHAEL P. DOYLE, OF BROOKLYN, NEW YORK

BORING AND FACING TOOL WITH FEED ATTACHMENT

Application filed May 13, 1931. Serial No. 536,965.

This invention relates to an improved tool for boring and refacing valve seats and, more particularly, to a tool of this character which can be accurately and quickly positioned in operating position and which can be used in such a manner that the cutter portion thereof may be positively fed against the valve seat and positioned with respect thereto so that a required degree of cut may be accomplished and when that degree of cut has been completed the operation of the tool will cease to feed the cutter towards the valve seat.

A further object of the invention is to provide a tool of this character whereby the said tool is made adaptable for use in refacing valve seats in various types and sizes of valve casings, or reborning cylinders on gasoline engines.

A further object of the invention is to provide a device of this character which will be highly efficient, durable in operation and sturdy in construction.

Other features and advantages of my invention will hereinafter appear.

25 In the accompanying drawing:

Figure 1 is a view in elevation, mainly in section of my improved tool and showing it in operative position on a valve casing;

Fig. 2 is a transverse section of Figure 1 as seen along the plane indicated by the line 2—2 in Figure 1 and looking in the direction of the arrows;

Fig. 3 is a plan view of a portion of the mechanism of the tool.

35 In describing the invention, reference will be made to the drawing by similar characters placed on corresponding parts throughout the several views.

In illustrating my improved refacing tool, 40 I have shown the same applied to an ordinary type of valve casing 1 having a valve seat 2 therein and from which seat extends an attaching neck 3. The valve casing is shown with an opening 4 which is normally adapt- 45 ed to be closed by a cover plate. The casing is also provided with the usual threaded openings 5 adapted to receive the securing bolts or studs for the valve cover.

While I have shown my tool as applied 50 to a particular type of valve casing, it is to be

understood that the same may be applied to a number of different types of construction of valve casings and is not limited for use in connection with the one illustrated in the drawing.

55 The refacing tool is adapted to be secured to the valve casing by means of a support or brace 6 formed with the extensions 7, 7. These extensions have elongated slots 8 and are adapted to be secured to the casing by means of the screw threaded bolts 9 which are inserted into the threaded openings 5 of said casing. The support or brace 6 is provided with an interiorly threaded neck portion 10 which is adapted to receive the reduced threaded portion of a hollow tubular member 11.

60 This particular construction of the support or brace 6 makes the tool adaptable so that it may be fitted to any gasoline engine 65 by means of a reducing nipple and to be used for boring out the cylinders of the same or for facing the valve seats or worn valve chambers in pumps.

65 The bridge effect produced by means of the construction of the support or brace 6 also allows the operator of the tool ample room to reach into the valve casing to connect or remove the cutting element employed or any other of the parts of the tool which extend down into the casing without the necessity of removing the tool from its position with respect to the valve casing. This particular construction of the support or brace also enables the operator to see the operation of the cutter within the valve casing.

70 Extending through the tubular member 11 is the shaft 12 which is formed at its upper end with the angular portion 45 and at its lower end with the tapered opening 16. The shaft 12 also is formed with the collar 13, said collar being positioned so that it will have a bearing contact with a fiber washer 15a positioned against the inner face of the hollow tubular nut member 14.

75 The tubular hollow nut member 14 is interiorly threaded and is adapted to be received on the exteriorly threaded portion of the hollow tubular member 11.

80 The tapered opening 16 of the shaft 12 is 100

adapted to receive an extension shaft 17 provided with the tapered end 18 and the internally threaded open end 19.

The lower end of shaft 12 is provided with 5 a slot 21 which is adapted to receive a tool or instrument therein above the end of the tapered portion of the shaft 17 when said shaft is wedged into place in the tapered opening 16 of shaft 12 so that said shaft 17 10 may be forced out of its wedged connection with shaft 12 when desired.

The shaft 17 is adapted to have removably connected therewith, in its threaded open end, the cutting tool 22 carrying the cutter 20. 15 The said cutter 20 is positioned through a radially disposed slot in the shaft of the tool and is maintained in its proper cutting position by means of a suitable wedge 24.

The shafts on which the cutter 20 is positioned may be of any desired length and different lengths of said shafts are used according to the depth of the valve casing in connection with which the tool is being used.

The cutting tool has the extension 26 to 25 which is secured in any suitable manner the centering spider designated generally at 27. The said spider is formed with the three hollow projecting arms 28, 29 and 30. Each of these arms are internally threaded so as to receive the screw threaded bolts 31. The bolts 31 are provided with the pointed heads 33 and may be adjusted with respect to the threaded arms 28, 29 and 30 and held in adjusted position by means of the lock nuts 32. 30 35 Each of the arms of the spider are provided with a pit point 34. Each of these points is positioned at an equidistant point from the end of said arms.

Secured to the head portion 15 of the nut 40 member 14 in any suitable manner as at 35 is the outwardly extending arm 36 having slidably mounted therein at its free end the square pin 37, with enlarged ends 37^a. The pin 37 may be held in any desired position 45 with respect to the arm 36 by means of a key 38.

One face of square pin 37 is formed with a rounded portion 37^b, said rounded portion extending downwardly from the top of pin 50 37 to about half way of its length.

Mounted on the shaft 12 above the nut 14 is a collar 39. This collar is secured to shaft 12 by means of a taper pin 38 which is adapted to pass through said collar and shaft. Between the collar and the nut 14 is provided a 55 fiber washer 39^a.

The collar 39 is provided with a hollow exteriorly threaded extension 40 which is adapted to receive therein the pin 41. The pin 41 is provided with a shoulder 42 and is yieldingly maintained in the opening of threaded extension 40 by means of the internally threaded nut 43 which is adapted to be screwed on the threaded portion of extension 60 65 40 of collar 39 and by the spring 44 which

is positioned so as to abut against the shoulder 42 of the pin 41 and the end of the collar extension 40. The nut 44^a is provided in conjunction with the internally threaded nut 43 to regulate its position with respect to the collar extension 40.

The collar 39 and its extension 40 is positioned so that the end of pin 41 will normally abut against the rounded portion of pin 37 of the arm 36 when the shaft 12 is rotated and thereby moves the arm 36 in the direction of the rotation of the shaft 12.

A suitable lever not shown in the drawing and adapted to manually rotate shaft 12 of the tool may be positioned so as to engage with the end 45 of said shaft.

In applying my tool to the use for which it is intended I first select the proper length of shaft 22, with its cutter member and extension 26 secured thereto, which will properly position said cutter with respect to the valve seat to be refaced. This shaft 22 is secured to the shaft 17 and the tapered end of shaft 17 is then wedged into the tapered opening at the lower end of shaft 12 of the tool.

The cover of the valve casing is then removed and the tool is placed into the valve casing so that the centering spider is disposed in the neck 3 of the casing and the cutter 20 rests on the valve seat 2, and the support or brace 6 is mounted on the outside of the casing.

The centering spider member is then positioned with respect to the interior of the neck 3 so that the shaft 13 is accurately centered in the valve casing and the cutter is positioned in proper cutting relation with the valve seat. This is accomplished by manipulating the nuts 32 and the screw bolts 31 so that the pointed ends of the heads of said bolts will be equidistant from the pin pits 34 in the arms of the spider when they are in engagement with the side walls of the neck 3. The proper equal distances may be measured by any suitable instrument using the pit points 34 as one point and the side walls of the neck 3 as the other point in the positioning operation.

When the tool has been properly centered by means of the positioning of said spider the bolts or screws 9 are then placed through the slots 8 of the extensions 7 of the brace 6 and the tool secured to the valve casing so as to prevent any improper vibration or movement during the operation thereof.

The shaft 12 is then rotated by the handle which has been engaged with the end 45 thereof and such rotation is imparted to the cutting tool 22 and its cutter 20 which is positioned on the valve seat. The rotation of the shaft 12 causes the collar 39 and its extension 40 to rotate therewith and the end of the pin 41 will engage with the rounded portion 37^b of the square pin 37 secured in the end of the arm 36 and thus cause the nut 14 to rotate

downwardly on the screw threaded tubular member 11. As the nut 15 moves downwardly the shaft 12 also moves downwardly causing a greater pressure to be placed upon the cutter 20 against the face of the valve seat and thereby causing said cutter to make a cutting pass over the face of the valve seat.

When the cutter 20 has been fed against the valve seat face in making its cutting pass, 10 by the downward pressure thus exerted to it to the extent that it resists such pressure, the further rotation of the shaft 12 will cause the rounded end of pin 41 to be forced inwardly against the action of spring 44 by reason of 15 its contact with the rounded portion of pin 37 and it will thus slide past the rounded portion of pin 37. The downward rotation of the nut 14 thus will be arrested until the end of pin 41 is again brought into contact with 20 the pin 37 by the further rotation of shaft 12.

When the downward rotation of the nut 14 is thus arrested the cutter having made its cut in the valve seat the same will not make another cutting pass until the nut 14 is again 25 caused to move downwardly by reason of the rotation of arm 36 by means of the pin 41 engaging the pin 37.

If desired at any time the square pin may be released from its contacting position in 30 arm 36 by unloosening the pressure thereon as applied by the key 38 and said pin may be allowed to drop below the path of the pin 41 as the shaft 12 is rotated. When this is done, of course, the nut member 14 will not 35 progress downwardly on the threaded part of said member 11 as shaft 12 is rotated and the cutter 20 will merely pass over the surface of the valve seat without any pressure being applied to it.

40 It will be seen that by the construction of tool above described and illustrated in the drawing, the cutter can be accurately positioned with respect to the valve seat and any desired depth of cut for refacing the valve 45 seat may be made with the cutter and when such cut has been accomplished the cutting action of the cutter may automatically be stopped.

It is also obvious that valve seats of any 50 number of types of valve casings may be trued or reshaped and by reason of the facility of applying different lengths of extensions to the shaft 12 and that in this respect the tool is highly advantageous and useful.

55 Various slight changes may be made in the general form of the parts described without departing from my invention, and, hence, I do not limit myself to the exact details set forth but consider that any variations with- 60 in the spirit and scope of my invention are equally comprehended by the foregoing disclosure.

What I seek to secure by United States Letters Patent is:

65 1. A tool of the class described comprising

a support adapted to be adjustably secured to the valve casing and having an upwardly extending exteriorly threaded tubular extension, a hollow interiorly threaded tubular element having a head portion with an 70 opening therethrough, and mounted on said threaded tubular extension and adapted to be rotatably moved with respect thereto, a shaft having rotary mounting in said support and extending through said threaded extension and the opening in the head portion of said tubular element, a collar integrally secured to said shaft and positioned within the hollow interiorly threaded element so as to contact with the interior face of the head portion thereof, an arm secured to and extending outwardly from the head portion of said tubular element and slidably carrying at its outer end, a square pin with a rounded portion formed thereon, means 75 secured to said shaft adapted to engage said pin when said shaft is rotated and to cause the said pin and its associated arm and the tubular element to be rotated with said shaft so as to cause said tubular element to be moved downwardly along the threaded portion of the exteriorly threaded tubular extension of said support and thus cause said shaft to move downwardly into the valve 80 casing, an extension shaft removably secured to the lower end of said shaft, a cutting tool removably secured to the lower end of said extension shaft and provided with a cutting element positioned so as to contact 85 with the valve seat of said valve casing when 90 said first mentioned shaft is moved downwardly by the downward progression of said tubular element on the threaded extension of said support, and means secured to the lower end of said cutting element to center said tool with respect to the valve casing and its 95 valve seat.

2. A tool of the class described comprising a supporting means for supporting and securing said tool in operative position with respect to the opening in a valve casing, an exteriorly threaded tubular member secured to said supporting means, a shaft having rotary mounting in said supporting means and in said exteriorly threaded tubular member 110 and adapted to extend downwardly into the interior of the valve casing, an extension shaft removably secured to the lower end of said shaft, a cutting tool removably secured to the lower end of said extension shaft and comprising a shaft having a cutter element and a positioning element mounted thereon, said cutter element being positioned on said shaft so as to engage the face of the valve seat in the casing and said positioning element being disposed on said shaft so as to make contact with the inner wall of the neck of the casing below the valve seat, a tubular 115 interiorly threaded nut rotatively mounted 120 on said exteriorly threaded tubular member 125 on said exteriorly threaded tubular member 130

secured to said support, said tubular threaded nut being provided with an outwardly extending arm, an abutment pin slidably mounted in the end of said arm, a collar 5 formed on said shaft and positioned so as to have contact with the interior face of the head portion of said tubular nut, a collar fixedly secured to said shaft above said tubular nut and positioned so as to have bearing 10 contact with the upper and outer face of the head of said nut, said collar being provided with a tubular exteriorly threaded extension, a pin mounted in said tubular extension of said collar and positioned so that it will engage 15 with said abutment pin, and means adjustably secured to said extension for holding said pin in yielding contact with a spring in said tubular extension, means on said shaft for rotating the same and its connected 20 parts including the cutter in said support and to cause said pin to abut against said abutment pin and cause the rotation of said nut downwardly on the threads of said tubular extension and thus cause the cutter to be 25 positively fed with a bearing contact against the valve seat until said resilient pin is forced past the said abutment pin.

In testimony whereof I have hereunto set my hand on this 12th day of May, A. D., 30 1931.

MICHAEL P. DOYLE.
